UNITED STATES PATENT OFFICE.

BERTRAM LENZEN, OF PROVIDENCE, RHODE ISLAND, ASSIGNOR OF ONE-HALF TO GEORGE C. RUECKERT, OF PROVIDENCE, RHODE ISLAND.

RING-TRAY.

SPECIFICATION forming part of Letters Patent No. 710,475, dated October 7, 1902.

Application filed March 14, 1902. Serial No. 98,139. (No model.)

To all whom it may concern:

Be it known that I, BERTRAM LENZEN, a citizen of the United States, residing at Providence, in the county of Providence and State of Rhode Island, have invented certain new and useful Improvements in Ring-Trays, of which the following is a specification.

My invention relates to that class of trays for holding jewels commonly known as "ring-trays," and has for its object the ends commonly sought in receptacles of such a character—namely, security, facility of action, and a small cost.

To these ends my invention consists in the novel construction and combination of parts hereinafter described, and illustrated in the accompanying drawings, wherein—

Figure 1 is a top plan view of a tray with a portion of the cushion-strips removed; Fig. 2, a vertical transverse section of the same on line *x* *x* of Fig. 1; Fig. 3, a similar view of the same with the locking-strip in disengaged position; Fig. 4, a perspective view of a portion of a locking-strip; Fig. 5, a longitudinal section of a portion of the tray on line *y* *y* of Fig. 1; Fig. 6, a similar section on line *z* *z* of Fig. 2, and Fig. 7 detail views of a modified form of spring mechanism.

Like letters of reference indicate like parts throughout the views.

My tray consists of a rectangular body *A*, with upright sides or walls *a* *a'* *a''* *a'''*. The floor of the tray is provided with a parallel series of channels *b*, in which run metallic locking-strips *B*, somewhat shorter than the width of the tray, to allow longitudinal movement therein of said locking-strips, whose outer ends pass through openings *c* in the front wall of the box and terminate in handles *d*. Excessive outward movement of these strips is prevented by projections *e* thereon adjacent the inner face of the wall *a*. In detail the locking-strip *B* is composed of a thin strip of metal having upon its upper face at regular intervals a series of integral prongs or fingers struck up from the body of the strip and directed toward its handle and whose points lie in a plane parallel to the plane of the body. A spiral spring *g* extends across the tray adjacent the inner face of the wall *a* and is fixed to the floor of the box by pins *h* or other fastening means at its ex-

tremities and intermediate each locking-strip. The stops *e* are thus intermediate the spring and wall.

55

Resting upon the floor of the tray and at right angles to the direction of the locking-strips *B* are a series of contiguous fabric-covered bars *i*, with ribbed sides to allow spaces *j* for the insertion of rings *k*. These bars have transverse channels *l* in their lower portions to allow passage therethrough of the prongs *f* when the locking-strip is vibrated. The bars *i* cover the entire surface of the tray and are preferably secured at their extremities by beveled strips *m*, fixed to the walls of the box.

When it is desired to insert or withdraw a ring from its receptacle, the operator presses inwardly upon the handle *d* of the locking-strip whose prong corresponds with said ring and against the tension of spring *g*, whereupon the engaging prong is forced out of the plane of the ring. Upon releasing the handle *d* the locking-strip reverts to its original position and its prong engages the ring.

It is evident that my invention may include a spring mechanism such as shown in Fig. 7, where a coil-spring *g'* bridges the locking-strip and contacts with the back of a prong and its coiled terminals *n* and *o*, fixed to the floor of the tray. The spiral spring *g* may, if preferred, traverse the tray transversely to the locking-strip at any other point than adjacent the wall *a*, provided it contacts with the backs of a series of the prongs *f*.

Having thus described my invention, what I claim as new, and desire to secure by Letters Patent, is—

1. In a ring-tray, the combination with the tray proper, having a floor provided with a series of channels, of locking-strips longitudinally movable therein, projections on said strips within the tray to prevent excessive outward movement, prongs extending from the upper faces of said strips, a spring disposed at right angles to said strips and between which and the front wall of the tray said projections are disposed, and bars disposed horizontally and transversely to said strips having channels, and spaces for the insertion of rings, substantially as described.

2. In a ring-tray, the combination with a tray, of slidable metallic locking-strips hav-

ing integral prongs extending from the faces thereof, means for retaining the locking-strips within the tray, a series of bars fixed side by side above the locking-strip and at right angles thereto and formed with transverse channels to afford clearance for the prongs, means carried by said bars for retaining them in place and a horizontal spring attached to the casing upon opposite sides and disposed transversely to the locking-strips and adapted to engage said retaining means, substantially as described.

3. In a ring-tray, the combination with a tray, of slideable locking-strips having prongs, fabric-covered bars within said tray above and at right angles to the locking-strips and

having transverse channels upon their under faces for the passage of said prongs and spaces into which the fabric is extended and which are adapted for the reception of rings, bevelled strips within the tray engaging the ends of said bars, stop-pins on the locking-strips and a transverse spring engaging the stops to force the locking-strips outward, substantially as shown and described. 20 25

In testimony whereof I have affixed my signature in presence of two witnesses.

BERTRAM LENZEN.
